E. T. SHERMAN

DOOR LATCH

Filed July 27, 1920

INVENTOR
E. T. Sherman
BY HIS ATTORNEYS

William Merchant

UNITED STATES PATENT OFFICE.

EDWARD T. SHERMAN, OF MINNEAPOLIS, MINNESOTA.

DOOR LATCH.

Application filed July 27, 1920. Serial No. 399,366.

To all whom it may concern:

Be it known that I, EDWARD T. SHERMAN, a citizen of the United States, residing at Minneapolis, in the county of Hennepin and 5 State of Minnesota, have invented certain new and useful Improvements in Door Latches; and I do hereby declare the following to be a full, clear, and exact description of the invention, such as will enable 10 others skilled in the art to which it appertains to make and use the same.

My invention has for its object to provide a simple and improved door latch, the term door latch being, herein, in a broad sense to 15 include a latch for securing any kind of swinging closure, such as, a gate for example, in position for closing a passage way or an opening.

Generally stated, the invention consists of 20 the novel devices and combinations of devices hereinafter described and defined in the claims.

In door latches as now generally constructed, the latch bar moves in a vertical 25 plane or in a plane parallel to the door and perpendicular to the planes in which the door swings. Moreover, in such door latches, the latch bar is raised by camming action of an inclined surface on a fixed latch 30 plate, so that there is very considerable lateral thrust on the latch bar, which creates a friction that sometimes makes it impossible and always difficult to close the door, without lifting the latch bar, by manipulation of 35 the latch lever.

I overcome the above difficulty by arranging the latch bar to move in a plane that is oblique to the door and hence moves in the plane that is at a much less angle to the 40 horizontal line of lateral thrust, than in the older form of latch.

This feature and others will be more fully disclosed in connection with the description of the accompanying drawings, wherein like 45 characters indicate like parts throughout the several views.

Referring to the drawings:

Fig. 1 is a front elevation showing the latch applied to the door, the door being in 50 a closed position;

Fig. 2 is a view corresponding to Fig. 1, but showing the door in an open position;

Fig. 3 is an enlarged section on the line 3—3 of Fig. 1;

Fig. 4 is a vertical section on the line 4—4 55 of Fig. 1; and

Fig. 5 is a transverse section on the line 5—5 of Fig. 4.

The numeral 4 indicates a door frame set 60 in a wall 5.

The numeral 6 indicates a door hung from 65 the frame 4, by hinges 7 and provided with an ordinary pull or head piece 8 on its inner side.

The latch bar 9 is pivoted to the boss 10, 70 by means of an oblique screw or rivet 11, and its free end projects beyond the free edge of the door for engagement for a lock shoulder 12 of a latch plate 13 and which plate, by means of screws or the like, is rigidly fastened to the door casing 4.

By reference to Fig. 5, it will be noted 75 that for the reception of the pivot end of the latch bar 9, the boss 10 is provided with a horizontal diametrical passage, so that the latch bar may be applied projecting from either toward the right or toward the left. This permits the latch to be applied to a door that is hinged to either edge without requiring the bosses to be made in right or 80 left designs.

The latch bar 9 works through a slot 14 formed in a guide plate 15, which by means 85 of screws or the like, is rigidly secured to the free edge of the door. Here it is highly important to note that the latch-bar-guide-slot 14 is oblique to the face of the door. More definitely stated, the said slot 14 extends at an acute angle to the plane of the door and at an obtuse angle to the horizontal plane 90 in which the door swings, and said latch bar 9 moves pivotally in said oblique plane in which the guide slot 14 is extended.

By reference particularly to Fig. 3, it will be seen that the latch plate 13, outward of 95 its notch 12, has an inclined cam surface 16, that will cam upward the free end of a latch bar when the door is swung to a closed position. By reference to the same view, it will be noted that the edge of the lock shoulder 100 is not only oblique to the plane 7 of the door, but is at a slightly greater angle thereto than the slot 14; and this is important because when the latch bar engages the shoulder 12

and is dropped down into said notch, the camming action between the same and said oblique shoulder will bring the door to a more closely or tightly closed position.

5 Again, by reference to Fig. 3, it will be noted that the latch gate 13, which is countersunk into the casing, is provided at its lower outer portion, with a dependent stop lug or portion 17 that engages the outer face of 10 the door frame and assists in positioning the latch plate when it is first applied, and in holding in proper position after it is applied. For the same reason, the guide plate 15 (see Fig. 2) is provided respectively, with upper 15 and lower stop lugs or shoulders 18 and 19 that engage the outer face of the door 6. The numeral 20 indicates a latch lever that is pivoted to the door, extends through the door and is arranged to lift the latch bar 9 20 substantially in the customary way.

With the above described latch, it is evident that when the door is swung closed and the free end of the latch bar is engaged with the cam surface or edge 16 on the latch plate 13, said latch bar will be raised by a force that is very nearly in straight line 25 with the guide slot 14 and hence does not produce much lateral pressure on the latch bar in such lifting action and thus reduces 30 to a minimum the friction between the latch bar and its guide plate.

This improved latch has been put into actual use and not only found efficient but superior to the older form of latch. The 35 latch as demonstrated in practice, will automatically lock itself under very slight force applied to the door in a direction tending to close the door. Otherwise stated, the latch does not perceptibly interfere with the 40 natural closing movement of the door. Moreover the wear on this latch is much less than the wear on the ordinary latch, hitherto used.

What I claim is:

1. The combination with a door frame and 45 a door hinged thereto, of a latch bar pivoted to the door and mounted to move in a plane that is oblique to the plane of the door, and a latch plate on the door frame having a lock shoulder with which said latch bar is 50 engageable, the said lock shoulder being oblique and at a greater angle to the plane of the door than is the plane in which the latch bar moves, and a means of elevating

and dropping the said latch bar into engagement with said shoulder under closing movement of the door. 55

2. The combination with a door frame and door hinged thereto, of a latch bar guiding plate secured to the free edge of the door and having a guide slot that is oblique to 60 the plane of the door, a latch bar pivoted to the door and movable in the oblique slot of said guide plate, and a latch plate secured to the door frame and provided with a lock shoulder with which the free end of the 65 latch bar is engageable, the said lock shoulder being oblique and at a greater angle to the plane of the door than is the plane in which the latch bar moves, and said latch bar having a cam surface for camming said 70 latch bar into engagement with said shoulder under closing movement of the door.

3. The combination with a door frame and a door hinged thereto, of a latch bar guiding plate secured to the free edge of the 75 door, a latch bar pivoted to the door and movable in an oblique slot of said guide plate, a latch plate secured to the door frame and provided with an oblique lock shoulder with which the free end of the latch bar is 80 engageable, an inclined camming edge on the latch plate approximately at right angles to the plane of the latch bar, operative to elevate the free end of the latch bar under closing movement of the door with a force 85 approximately in a straight line with the guide slot.

4. The combination with a door frame and a door hinged thereto, of a latch carrying member secured to the door, a latch pivoted 90 to said member by a pivot extending downwardly at an angle to the plane of the door and guided to move in a plane at an angle to the door, a latch plate secured to the door frame and having a notch therein, the 95 forward edge of which is inclined to the door at a slightly greater angle than the latch.

5. The structure set forth in claim 4, said latch carrying member having an aperture 100 extending entirely therethrough at an angle to the plane of the door so that said latch can be secured thereto by said pivot and extend at either side thereof.

In testimony whereof I affix my signature. 105
EDWARD T. SHERMAN.
